UNITED STATES PATENT OFFICE.

BENJAMIN F. HUTCHES, JR., OF ALLENDALE, NEW JERSEY.

CIRCUIT-CHANGER FOR ELECTRIC RAILWAYS.

1,087,537.

Specification of Letters Patent.

Patented Feb. 17, 1914.

Application filed March 14, 1912. Serial No. 683,693.

To all whom it may concern:

Be it known that I, BENJAMIN F. HUTCHES, Jr., a citizen of the United States, residing at Allendale, county of Bergen, and 5 State of New Jersey, have invented a new and Improved Circuit-Changer for Electric Railways, of which the following is a specification.

This invention relates to a circuit changer 10 of novel construction which is more particularly designed to be employed in conjunction with automatic control systems for electric railways, such as described in a pending patent application filed by me Feb- 15 uary 7th, 1912 under Serial No. 676,003.

Briefly stated the invention comprises a 20 novel device which is controlled by the working circuit of the cars or trains, and which effectively prevents collisions by automatically cutting off the current from cars located in the safety zones adjoining that zone through which a car is traveling.

The device further includes novel means for gradually admitting the electric current to zones which were previously cut off, so as to prevent any damage to the motors, etc., carried by the car situated in said zones.

The invention also comprises various novel features of construction as more fully pointed out in the appended claims.

In the accompanying drawing: Figure 1 is a diagrammatic view of a circuit changer embodying my invention; Fig. 2 a wiring diagram, illustrating the circuit changer applied to a single track having three switches, and Fig. 3 a diagram showing the additional resistance contained in the cars.

The numerals 10 and 11 indicate a pair of electromagnets arranged on one side of a 10 common or main armature 12, while on the other side thereof is provided an electromagnet 13. Armature 12 is fulcrumed at 14 and is furnished at its free end with a toothed sector 15 that meshes into a similar 20 sector 16 rotatably mounted on a pin 17. Sector 16 is provided with an integral arm or swinging member 18, the enlarged free end of which is adapted to ride over the current receiving contacts 19, 20 of resistances 21, 22 respectively. To arm 18 is secured by insulator 23 a metallic shoe or bridge 24 adapted to consecutively engage the contacts 25, 26 of resistances 27, 28 respectively. Opposite armature 12, electromagnets 10, 11 are provided with a common auxiliary armature 29 which is normally retracted

from said electromagnets owing to the resiliency of the upper reduced section of said armature.

Each of the electromagnets 10, 11, 13 is 60 provided with a primary low resistance coil and with a secondary high resistance coil as clearly illustrated in Fig. 1. Thus electromagnets 10 and 11 carry the primary windings 30, 31 and the secondary windings 32, 33 respectively, while electromagnet 13 is provided with a primary winding 34, and a secondary winding 35. The various windings coöperate with the trolley wires of the electric railway, Fig. 1 illustrating the trolley wires 36¹, 37¹ pertaining to a coöperating track switch A¹ (Fig. 2), said wires being insulated at 38 from the bifurcated ends of the flanking single trolley wires 39, 40. Winding 30 of electromagnet 10 is by wire or conductor 41 connected to trolley wire 40 and by wire 42 to the outer contact 20, a branch 43 leading from wire 41 to the outer contact 26. In similar manner, winding 31 of electromagnet 11 is by wire 44 connected to trolley wire 39 and by wire 45 to the outer contact 19, a branch 46 leading from wire 44 to the outer contact 25. Winding 34 is by wire 47 connected to both of the trolley wires 36¹, 37¹, and by wire 48 and flexible cable 49 to shoe 24. Armature 12 is by conductor 50 connected to the main feed wire 51, while a branch 52 leads from armature 12 to the auxiliary armature 29. One end of the secondary winding 32 is directly connected to wire 41 and the other end thereof is by wire 53 connected to branch 52. In similar manner secondary winding 33 is with one end directly connected to wire 44, while its other end is by wire 54 connected to branch 52. One end of the secondary winding 35 of electromagnet 13 is directly connected to wire 47, its other end being connected by a wire 55 to a stationary contact 56 against which armature 29 rests when the electromagnets 10, 11 are deenergized.

In Fig. 2 three track switches A¹, A², A³ are shown, while the single track sections are marked B¹, B², B³, B⁴ respectively. The above switches coöperate with trolley wires or third rails 36¹, 37¹; 36², 37²; and 36³, 37³ respectively while the single wire sections are marked 39, 40, 57, 58 each single wire being insulated at 38 from the flanking switch trolley wires.

In general explanation it may be stated

that a circuit changer as described is provided for each track switch, the arrangement being such that when a car travels along a single track section, current is supplied to the corresponding trolley wire section through both of the circuit changers arranged at the track switches that flank said single track section. So for instance if a car C^1 travels in the direction of the arrow (Fig. 2), the armatures 12 of circuit changers D^2 and D^3 pertaining to track switches A^2 and A^3 are swung toward the left (by reasons herein-after more fully explained). In this way arms 18 of these circuit changers are swung toward the right, so as to bridge the outermost contacts 19, 20. Part of the working current necessary for operating car C^1 flows from feed wire 51, through wire 50, armature 12 of circuit changer D^3 , sectors 15, 16, arm 18, outer contact 19, wire 45, winding 31 of electromagnet 11, and wire 44 to trolley wire 57. The other part of said working current is supplied to trolley wire 57 through circuit changer D^2 , the current here flowing from feed wire 51, through branch 50, armature 12, sectors 15, 16, arm 18, contact 20, wire 42, winding 30 of electromagnet 10, and wire 41. In order to maintain armatures 12 in their proper positions, even if the controller 59 of the car is turned to cut off the motor current, an additional comparatively high resistance 60 is interpolated between the conductors 61, 62 leading from the controller to the car wheels and trolley pole respectively. In this way a small current will continuously flow through electromagnets 11, 10 of circuit changers D^3 , D^2 respectively as long as the car passes track section B^3 , said small current being sufficient to maintain armatures 12 attracted by said electromagnets.

It is evident from Fig. 2 that the car C^1 while traveling along track B^3 is effectively protected against head on and rear end collisions, as cars which may be located within switches A^2 and A^3 cannot leave said switches, the reason being that car C^1 while running from switch A^2 into track B^3 has automatically cut off the current from trolley wires 36¹, 37¹ and 36², 37² as will be hereinafter more fully described. Fig. 2 shows the arms 18 of circuit changers D^2 and D^3 swung toward the right, so that shoes 24 are out of engagement with the respective contacts 25, 26 and therefore electric current cannot be supplied through wires 48, 49, windings 34, and wires 47 to the switch trolley wires. Thus for instance a car C^2 shown to be located in switch A^2 cannot proceed since the current is cut off from the trolley wires 36², 37² as above described. As soon however as the trolley 63 of car C^2 leaves trolley wire 57 and engages wire 37², the current previously flowing through electromagnet 11 of circuit changer D^2 and

through electromagnet 10 of circuit changer D^2 is interrupted, so that both of their armatures 12 and 29 will be released and armatures 29 engage contacts 56. In this way a circuit is closed by the armature 29 of circuit changer D^2 , the current flowing from feed wire 51 through wires 50, 52 of circuit changer D^2 , armature 29, wire 55, winding 35 of electromagnet 13, wire 47, trolley wires 36², 37² and cars C^1 , C^2 to the track rails. Electromagnet 13 of circuit changer D^2 is thus energized to attract armature 12 and thereby swing arm 18 toward the left. In this way, shoe 24 will ride over contacts 25, 26 until it bridges the outermost of such contacts. At the same time two exciting circuits will be established, which cause the arms 18 of the flanking circuit changers D^3 , D^1 to be swung toward the right and thus supply the necessary working current to shoe 24 of circuit changer D^2 thereby enabling both of the cars C^1 , C^2 to proceed. Of one of said exciting circuits mentioned, the current flows from feed wire 51 to branches 50, 52 of circuit changer D^3 , thence through wire 54, secondary winding 33 of electromagnet 11, wire 44, trolley wire 57, wires 41, 43 of circuit changer D^2 , shoe 24, (which is now deflected toward the left), wires 49, 48, winding 34 of electromagnet 13, wire 47, trolley wires 36², 37² and cars C^1 , C^2 to the track rails A^2 . In this way, electromagnet 11 of circuit changer D^3 is energized to throw its arm 18 toward the right and by engaging contacts 19, establish the above described circuit for providing the working current to trolley wire 57, whence it will flow through wire 43 of circuit changer D^2 to trolley wires 36², 37² by following the same course as the above described first exciting current. The second exciting current flows from feed wire 51 through branches 50, 52 of circuit changer D^1 , thence through wire 53, secondary winding 32 of electromagnet 10, wire 41, trolley wire 40, wires 44, 46 of circuit changer D^2 and shoe 24 (which is now deflected toward the left) to rails A^2 in the manner described with respect to the first exciting current. Electromagnet 10 of circuit changer D^1 is thus energized to attract its armature 12 and thereby throw the co-operating arm 18 toward the right. In this way the necessary circuit for the working current is established, said current flowing from feed wire 51 through branch 50 of circuit changer D^1 , armature 12, arm 18, contact 20, wire 42, winding 30 of electromagnet 10, wire 41 and thence to cars C^1 , C^2 by following the same course as indicated with respect to the second exciting current. Both cars C^1 and C^2 are thus enabled to proceed, while upon their leaving the switch A^2 , the arm 18 of circuit changer D^2 will be automatically swung toward the right, the arms of the flanking

circuit changers D^s and D^t remaining in their right hand position, so that each of the trolley wires 57, 40 receives working current from both of its ends. The above mentioned reversal of the arm 18 of circuit changer D^s is due to the fact that as soon as both cars leave switch A^s the current previously flowing through winding 34 of the coöperating electromagnet 13 is interrupted, while existing currents will flow in analogous manner to that previously described through the windings 32, 33 of circuit changer D^s to attract armature 12 and cause arm 18 to be tilted to the right, thereby supplying the desired working current to contacts 19, 20. It will be observed that before each arm 18 arrives at one of its terminal positions, either the arm itself or its shoe (according to the direction in which the arm is swung) must ride over a plurality of contacts before reaching the outermost contacts. So for instance when an arm 18 is swung toward the right, it will ride over a number of contacts 19, 20 before engaging the outer contacts. As the several contacts 19 as well as contacts 20 are connected by resistances 21, 22 respectively, it is obvious that the working current supplied by arm 18 is but gradually supplied to the trolley wires, so as to prevent any damage to be done to the car motors, etc., in case their controllers are set to full speed, while arm 18 is thrown over to supply current to the trolley wires. For the same reason the contacts 25, 26 are connected by resistances 27, 28 respectively, so as to permit a gradual increase of the current supplied to shoe 49 and to the coöperating trolley wires.

It is obvious that the electromagnets 10, 11, 13 hereinabove referred to may be replaced by electromotors of a different nature, that is to say by other electrically actuated devices or electromotive agents capable of moving the various circuit closing elements.

46 I claim:

1. In a device of the character described, a first trolley wire, a pair of second trolley wires at opposite ends thereof and insulated therefrom, a plurality of opposed electromotors, an armature oscillating therebetween, first means coöperating with said armature for supplying electric current to the second trolley wires, second means independent of the first means for supplying electric current to said second trolley wires while said first means are disconnected from said second trolley wires, and third means controlled by the armature and insulated therefrom for conductively connecting the first trolley wire with the second trolley wires while current is supplied to the latter through the second current supplying means.

2. In a device of the character described, a pair of trolley wires insulated from each other, a pair of electromagnets, first means

controlled by one of said electromagnets for supplying electric current to one of said trolley wires, second means controlled by the other electromagnet for conductively connecting both of said trolley wires, and third means independent of the first means for supplying electric current to the first named trolley wire while said first means are disconnected therefrom.

3. In a device of the character described, a first trolley wire, a pair of second trolley wires at opposite ends thereof and insulated therefrom, a plurality of electromagnets, a swinging member adapted to be reciprocated thereby, first means engaged by said member when in one of its terminal positions for supplying electric current to the second trolley wires, second means engaged by said member when in its other terminal position for connecting said second trolley wires with the first trolley wire, and separate resistances connected to said first and second means.

4. In a device of the character described, a plurality of electromotors, a reciprocable member controlled thereby and carrying an insulated conductive bridge, two pairs of contacts adapted to be alternately closed by said member and bridge, and trolley wires connected to said contacts.

5. In a device of the character described, a plurality of electromotors, a reciprocable member controlled thereby and carrying an insulated conductive bridge, means for supplying electric current, a current receiving first contact adapted to be conductively connected to said current supplying means upon a movement of said member in one direction, a pair of second contacts adapted to be connected with each other by the bridge upon a movement of the member in the opposite direction, and trolley wires connected to said contacts.

6. In a device of the character described, a plurality of electromotors, a reciprocable member controlled thereby, means for supplying electric current, a series of current receiving first contacts adapted to be consecutively connected to said current supplying means upon a movement of the member in one direction, resistances intermediate said contacts, a series of pairs of second contacts, the contacts of said pairs being adapted to be consecutively connected with each other upon a movement of said member in the opposite direction, resistances intermediate said contact pairs, and trolley wires connected to said first and second contacts.

7. In a device of the character described, a plurality of electromotors, a reciprocable member controlled thereby and carrying an insulated conductive bridge, a first trolley wire, a pair of second trolley wires at opposite ends thereof and insulated therefrom, means for supplying electric current, two

13. In a device of the character described, a reciprocable main armature, a first and a second electromagnet adapted to move said armature in one direction, a third electromagnet adapted to move the armature in the opposite direction, each of said electromagnets being provided with a mutually connected primary and secondary winding, means for supplying electric current, means for permanently connecting the secondary windings of the first and second electromagnets to said current supplying means, means controlled by and including said main armature for connecting the primary windings of said first and second electromagnets to the current supplying means, and an auxiliary armature controlled by the first and second electromagnets for connecting the secondary winding of the third electromagnet to said current supplying means.
14. In a device of the character described, a reciprocable main armature, a first and a second electromagnet adapted to move said armature in one direction, a third electromagnet adapted to move the armature in the opposite direction, each of said electromagnets being provided with a mutually connected primary and secondary winding, means for supplying electric current, means for permanently connecting the secondary windings of the first and second electromagnets to said current supplying means, means controlled by and including said main armature for connecting the primary windings of said first and second electromagnets to the current supplying means, an auxiliary armature controlled by the first and second electromagnets for connecting the secondary winding of the third electromagnet to said current supplying means.
15. In a device of the character described, a reciprocable main armature, a first and a second electromagnet adapted to move said armature in one direction, a third electromagnet adapted to move the armature in the opposite direction, each of said electromagnets being provided with a mutually connected primary and secondary winding, means for supplying electric current, means for connecting the primary windings of the first and second electromagnets to the current supplying means, and an auxiliary armature controlled by the first and second electromagnets for connecting the secondary winding of the third electromagnet to the current supplying means.
16. In a device of the character described, an oscillating armature, first and second electromagnets adapted to swing said armature in one direction, a third electromagnet adapted to swing the armature in the opposite direction, an arm operatively connected to the armature, an insulated bridge carried by the arm, a pair of first contacts adapted to be engaged by the arm, a pair of second contacts adapted to be engaged by the bridge, and trolley wires connected to said contacts.
17. In a device of the character described, an oscillating armature provided with a toothed sector, first and second electromagnets adapted to swing said armature in one direction, a third electromagnet adapted to swing the armature in the opposite direction, an arm intergeared with the sector, an insulated bridge carried by the arm, a pair of first contacts adapted to be engaged by the arm, a pair of second contacts adapted to be engaged by the bridge, means for connecting the first contacts with the first and second electromagnets, means for connecting the bridge with the third electromagnet, and trolley wires connected to said electromagnets.
18. In a device of the character described, a reciprocable main armature, a first and a second electromagnet adapted to move said armature in one direction, a third electromagnet adapted to move the armature in the opposite direction, each of said electromagnets being provided with a mutually connected primary and secondary winding,

means for supplying electric current, means for permanently connecting the secondary windings of the first and second electromagnets to said current supplying means, means controlled by and including said main armature for connecting the primary windings of said first and second electromagnets to the current supplying means, an auxiliary armature controlled by the first and second electromagnets for connecting the secondary winding of the third electromagnet to said current supplying means, a first trolley wire, a pair of second trolley wires at opposite ends thereof and insulated therefrom, first conductors connecting the primary windings of the first and second electromagnets to the second trolley wires, a second conductor connecting the primary winding of the third electromagnet to the first trolley wire, and means also controlled by the main armature for connecting the first conductors to the primary winding of the third electromagnet.

19. In a device of the character described, an oscillating armature, first and second electromagnets adapted to swing said armature in one direction, a third electromagnet adapted to swing the armature in the opposite direction, an arm operatively connected to the armature, an insulated bridge carried by the arm, a pair of first contacts adapted to be engaged by the arm, a pair of second contacts adapted to be engaged by the bridge, and trolley wires connected to said contacts.

20. In a device of the character described, an oscillating armature provided with a toothed sector, first and second electromagnets adapted to swing said armature in one direction, a third electromagnet adapted to swing the armature in the opposite direction, an arm intergeared with the sector, an insulated bridge carried by the arm, a pair of first contacts adapted to be engaged by the arm, a pair of second contacts adapted to be engaged by the bridge, means for connecting the first contacts with the first and second electromagnets, means for connecting the bridge with the third electromagnet, and trolley wires connected to said electromagnets.
